UNITED STATES PATENT OFFICE.

SIDNEY PARKER, OF CHICAGO, ILLINOIS, ASSIGNOR OF TWO-THIRDS TO
W. O. OSGOOD, OF SAME PLACE.

BLAST-FURNACE.

SPECIFICATION forming part of Letters Patent No. 446,168, dated February 10, 1891.

Application filed August 29, 1889. Serial No. 322,342. (No model.)

To all whom it may concern:

Be it known that I, SIDNEY PARKER, a citizen of the United States, residing at Chicago, in the county of Cook and State of Illinois, have invented certain new and useful Improvements in Blast-Furnaces, of which the following is a specification.

My invention relates to blast-furnaces; and it consists in an improved construction and arrangement of apparatus, which will be fully described hereinafter, reference being had to the accompanying drawings, in which—

Figure 1 is a sectional elevation of a blast-furnace embodying my improvements. Fig. 2 is a plan view. Fig. 3 is a horizontal section of one of the tuyeres.

The general arrangement of the furnace A, boilers B, and superheater C will depend upon the lay of the ground or other circumstances; but where it is practicable the boilers should be placed at an elevation to permit a flue D to be extended from the top of the furnace to the bridge-wall of the boiler-furnace, so that the waste heat from the furnace is made the means of heating the boilers.

From the steam-domes H of the boilers one or more pipes F extend to one or more superheaters C, which are heated by separate fires, so as to rapidly and highly heat the steam which passes to coils J of such size as to secure an extended heating-surface, as shown in dotted lines in Fig. 2. The smoke-pipe E from the superheaters extends to the flue D. From the superheaters the steam-pipes P extend to the furnace and into the tuyeres thereof, so that the steam from the boilers, after being superheated, is directed from the tuyeres into the furnace in the same manner as the hot air in furnaces of ordinary construction. The pipe P is somewhat smaller than the tuyere, and air sufficient to support combustion is drawn in through the intervening space, the pipe and tuyere forming an inspirator. (See Fig. 3.) I have found that by heating the steam to a sufficiently high temperature the supply of air may be greatly reduced or entirely cut off.

By the use of highly-superheated steam I obtain a stronger and more available blast

than can be obtained by the use of air and a blowing apparatus. There is no vapor, as the steam enters the furnace at a temperature of from 1,200° to 1,500° Fahrenheit, and there is a most material reduction in the expense of the plant, the blowing-engine being wholly discarded and the cost of the superheaters being but a fraction of that of the ordinary air-heaters.

By placing the boilers at the top of the stack I can utilize the waste heat of the gases from the furnace not only for heating the boilers, but also for a preliminary heating or roasting of the ore. Thus there is an endless belt 2 passing over drums 3 and extending through the flue D, onto which belt the ore is dumped and over which the heated gases pass in contact with the ore, which is gradually fed into the furnace as the belt moves, driven by any suitable motor. This device may be used in all furnaces.

It is customary to surround furnaces and heated structures of various kinds with water-jackets to prevent any undue increase in temperature, which is destructive to the structure and otherwise objectionable. Such water-jackets cost in large furnaces thousands of dollars and deteriorate rapidly. To avoid this expense and yet maintain the structure comparatively cool, I combine therewith a water-pipe q, arranged near the upper end with perforations so arranged as to direct streams of water against the sides of the furnace to trickle down the same. I have found that I can thus maintain the desired low temperature with as little water as is required for a water-jacket and at a fraction of the expense of erection and maintenance required to construct and use a water-jacket. A casting of thin metal surrounds the furnace to prevent the water splashing from the furnace and to direct the steam upward out of the way.

Without limiting myself to the precise construction and arrangement and application of parts and features shown, I claim—

The combination of a furnace with an independent steam-generator, and a conduit connecting the top of the furnace with the

flues of the steam-generator, and steam-pipes leading from the steam-generator to a superheater and from the superheater to the tuyeres of the furnace, and a smoke-stack communicating with the superheater and with the conduit, substantially as set forth.

In testimony whereof I have signed my

name to this specification in the presence of two subscribing witnesses.

SIDNEY PARKER.
